by Charles V. Tullar
His Attorney.

UNITED STATES PATENT OFFICE.

CROMWELL A. B. HALVORSON, OF LYNN, MASSACHUSETTS, ASSIGNOR TO GENERAL ELECTRIC COMPANY, A CORPORATION OF NEW YORK.

DESIGN FOR A LAMP FIXTURE.

Application filed June 4, 1929. Serial No. 31,545. Term of patent 14 years.

To all whom it may concern:

Be it known that I, CROMWELL A. B. HALVORSON, a citizen of the United States, residing at Lynn, in the county of Essex, State of Massachusetts, have invented a new, original, and ornamental Design for a Lamp Fixture, of which the following is a specification, reference being had to the accompanying drawing, in which the figure is a perspective view of a lamp fixture, showing my new design.

I claim:

The ornamental design for a lamp fixture substantially as shown.

In witness whereof, I have hereunto set my hand, this 25th day of May, 1929.

CROMWELL A. B. HALVORSON.
